UNITED STATES PATENT OFFICE

2,490,804

CRATE

William L. Haas, Buffalo, N. Y.

Application July 28, 1945, Serial No. 607,626

1 Claim. (Cl. 217—53)

1

This invention relates to a crate and more particularly to a crate for air freight, air transportation involving the special considerations of weight, strength and ability to readily pack the crates within a minimum space.

The crate shown is particularly designed for shipping air foils, such as the rudders, wing flaps, wing tips, stabilizers and ailerons of airplanes but it will be understood that the invention is not limited to any particular type of the freight to be crated.

One of the principal objects of the invention is to provide a crate which affords a high degree of protection to the article crated, particularly in protecting edges which are subject to injury such as the trailing edges of air foils.

Another object is to provide a crate which is light in weight, particularly in comparison with present methods of wrapping articles for air freight, particularly large articles, such as the air foils referred to.

Another object is to provide such a crate which reduces the packing time, thereby to facilitate both the crating and uncrating of the articles being shipped.

Another object is to provide such a crate which can be packed in any position and at the same time afford adequate protection, this permitting of the most advantageous use of the limited space within the airplane.

Another object is to provide such a crate which, when loaded, can readily be handled by machinery, thereby to minimize the necessity for manual handling which is particularly disadvantageous with large articles.

Another object is to provide such a crate in which the materials are low in cost and readily fabricated and normally are not particularly critical in time of war.

A further object is to provide such a crate which affords a high degree of protection and in particular holds the crated article against movement within the crate.

Other objects and advantages will appear from the following description and drawings in which:

Fig. 1 is a horizontal section through a crate for an airplane rudder and constructed in accordance with the present invention.

Fig. 2 is a perspective view thereof.

Fig. 3 is a vertical section, taking on line 3—3, Fig. 1.

The particular embodiment of the invention shown is a crate designed for a rudder, although it will be understood that the invention is not limited to any particular shape of article being

2

shipped. The crate is shown as having a base panel 5 of trapezoidal form supported by a pair of skids 6 which are secured to the underside of the base panel 5 along its longitudinal edges. It will be understood that, for strength, both the base panel 5 and the skids 6 can be made of plywood, this also being true of the other wooden parts of the crate. However, the invention is not limited to the use of plywood.

10 To the opposite longitudinal side edges of the base panel 5 are secured the lower ends of a plurality of side plates 8, 8a, etc., these side plates being arranged in pairs and each pair extending upwardly to a common apex so that the crate is generally triangular in section. While these are shown as a plurality of separate panels, it will be understood that they could be in the form of a single panel one on each side of the crate. The lower end of each of the side plates 8, 8a, etc., can be secured to the bottom panel 5 in any suitable manner and the upper ends of each pair of these side plates can be supported by a triangular fillet 10 interposed between the opposing upper end faces of the side plates. The 15 width and spacing of the side plates or panels 8, 8a, etc., can be selected to suit the particular piece of merchandise being crated. For example the panel 8a is shown as being substantially wider than the other panels to afford special protection to the adjacent part of the crated piece of merchandise. Further, the length of the side plates or panels 8, 8a, etc., can be designed to suit the shape of the crated piece of merchandise. Thus, for the airplane rudder for which the crate 20 illustrated was designed, the side panels are progressively longer from the panel 8 to the panel 8d, while the end pair of panels 8e are slightly shorter than the side panels 8d, the apices of the several side panels terminating in a curving line as shown.

These apices of the side panels 8, 8a, etc., are shown as being secured together by a pair of stringers 11, these stringers extending along opposite sides of the crate against the outer face 25 of each side plate or panel 8, 8a at the upper end thereof. These stringers can be secured by bolts 12 which extend through the pair of stringers 11, through the upper ends of the side plates or panels 8, 8a, etc., and through the triangular fillets 10. Each of these stringers can be made in the form of a continuous strip or can be jointed, as indicated at 13 in Fig. 2.

The crate is provided with a small triangular end head 15 and a large triangular end head 16, the small triangular end head being fitted and

secured between the base panel 5 and side plates or panels 8 and the large end head 16 being fitted and secured between the base plate 5 and the side panels 8e. For convenience in lifting the crate ropes 18 can be suitably secured to the end heads 15 and 16. To provide additional strength a metal strap or wood strip 20, or both, can be secured to the approximate centers of the side pieces or panels 8, 8a, etc. This strap can be secured in any suitable manner as by the fastening rivets 21.

The crate can be adequately padded with a very small amount of padding. Thus, to provide a cushioned endwise support for the piece of merchandise the end heads 15, 16 can be internally padded with triangular pieces 22 and 23 of padding material. The side padding can be provided at the large end of the crate by strips 24, 25 secured to the inner faces of the side pieces or panels 8e and at this end the base panel 5 can be padded by a strip 26 of padding extending between the lower ends of the pieces 24, 25 of padding. The smaller end of the crate can be similarly padded by side strips 28, 29 secured to the inner faces of the side pieces or panels 8 and a bottom pad 30 secured to the intermediate part of the bottom panel 5.

With the crate constructed as above described it will be seen that the crate is structurally rigid, particularly by reason of its triangular shape in cross section and by reason of the apices of the side pieces or panels being joined by the stringers 11 while the bottoms of these pieces are secured to the bottom plate or panel 5. This strength is further insured by the triangular end heads 15, 16 and by the intermediate strap 20. While strong the crate is extremely light in weight, particularly as compared with the present packing processes and the flexibility of the side panels 8, 8a, etc., permits of yieldingly engaging the sides of the crated article so as to hold it against displacement. The provision of the small amount of padding at the opposite ends of the crate also insures firm engagement with the crated article

and such padding can be provided elsewhere as may be found desirable by virtue of any peculiarity in the shape of the crated article.

It will also be seen that the filled crate can be handled by machinery and can be stowed in any position thereby to permit the most advantageous use of the limited space with any cargo plane. The crate is also made of inexpensive and readily obtained materials.

10 I claim as my invention:

A structurally rigid crate, comprising a base panel of substantial thickness and having longitudinal side edges and generally parallel end edges, a plurality of pairs of side panels secured in spaced relation directly to the opposite side edges of said base panel and each pair extending upwardly to provide a common triangular apex, a pair of stringers extending along the opposite outer sides of said side panels at the apices thereof, a triangular fillet fitted in the apex of each pair of side panels, fasteners extending directly through the pair of stringers and each pair of side panels and each of said triangular fillets, and a generally triangular end head secured on each end of said base panel and each fitted within and secured to the adjacent pair of said side panels.

WILLIAM L. HAAS.
